NECKTIE

Max J. Cohan, New York, N. Y.

Application June 4, 1951, Serial No. 229,793

1:Claim. (Cl. 2—146)

1

My invention relates to new and useful improvements in neckties and more particularly to the type or style of tie known as the four-in-hand, the primary object of the invention being to provide a tie of this character which, when applied to use and tied in the usual and conventional manner, will produce what is generally known to the trade and to the consuming public as a "Windsor knot," that is, the large, full, V-shaped knot, particularly desirable for use with collars of the spread type.

A further object of the invention resides in cutting the ordinary four-in-hand tie in such a manner and providing an auxiliary liner cut in a particular manner, so that when the tie is applied to use and tied in the customary manner known for four-in-hand ties, it will automatically produce the effect of the well known "Windsor knot."

A further object of the invention resides in cutting and folding the wide portion of a four-in-hand tie on a curve or arc for a predetermined length between the neck portion and the free end thereof.

A still further object of the invention resides in providing an auxiliary liner of predetermined length and having the side edges thereof cut on a curve or arc coincident with the curve or arc of the cut and fold of the body of the tie, and applied to the tie at a particular portion thereof.

A further object of the invention resides in providing a tie which is comparatively simple and durable in construction and one which will be very effective and beautiful when applied to use.

With these and numerous other objects in view, my invention consists in the novel features of construction, combination and arrangement of parts, as will be hereinafter referred to and more particularly pointed out in the specification and claim.

In the accompanying drawing, forming a part of this application:

Figure 1 is a plan view of the reverse side of a four-in-hand tie in outspread position, embodying my improvements.

Figure 2 is an enlarged fragmentary sectional view therethrough showing the relationship of the lining and the auxiliary or extra liner to the body of the tie, and further showing the curvature of the cut of the extra liner and the cut or fold of the body of the tie.

Figure 3 is a vertical sectional view therethrough, as seen on the line 3—3 of Figure 2.

Figure 4 is a fragmentary plan view of the liner

used with the tie, showing also the curvature of the cut of the side edges thereof.

Figure 5 is a similar view of the extra or auxiliary liner, also illustrating the curvature of the cut of the side edges thereof.

Figure 6 is a transverse sectional view through the tie, as seen on the line 6—6 of Figure 2, and

Figure 7 is a similar view, as seen on the line 7—7 of Figure 2.

The well known four-in-hand tie is known to be tied in a definite manner to produce a knot and the manner in which this is accomplished is also so well known no description thereof need be here set forth. The size of the knots resulting from the tying of such ties depends on various conditions. If the material is quite thin and there is little or no lining in the tie, naturally the knot will be quite small. Even when heavier materials are used and when linings are utilized, the knots may be small if they are not formed in the proper place in the length of the tie. Again, after being worn for some length of time and knotted tightly over a period of time, the material, even when reasonably heavy and lined, will lose its ability to form a reasonably large knot. The crushing of the material over a period of time will prevent such large knots being formed. Again, the manner in which the material is cut and folded, that is, with the side edges of the tie substantially straight, although tending to converge, will also prevent the ordinary four-in-hand tie, tied in the usual manner, from being formed with a reasonably large knot.

With the advent of what is known as the "spread" collars, that is collars wherein the tabs are spread or directed outwardly toward their ends, leaving a space or slot between the upper portions of the tabs for the reception of the necktie, the fashion of utilizing ties formed with large knots has prevailed, and has even been decreed by fashion stylists. Various attempts have been made to utilize the ordinary four-in-hand tie to meet the conditions, but there has been only one way of accomplishing the desired result and this has been to create what is known as the "Windsor knot." This is a large, full, V-shaped knot, and may only be formed by twisting and folding the tie in a particular manner, which differs materially from the manner in which the ordinary four-in-hand tie is folded and tied to produce the usual knot. In fact, the formation of the "Windsor knot" is so complex that the average man cannot learn how to accomplish it, even after he has been tutored. Thus, although there

is a great desire on the part of the purchasing public to utilize such knots in the use of four-in-hand ties with spread collars, the use thereof is only had by the few who have learned the intricacies of the accomplishment. There is a desire, therefore, and a need for a tie which will, through the conventional folding of a four-in-hand, produce results in the form of a knot substantially the same as the "Windsor knot," so that the public will have the benefit thereof without the difficulties encountered in learning how to produce, and actually producing such a "Windsor knot." My invention contemplates production of a tie to accomplish this result.

In describing the invention I shall refer to the drawing in which similar reference characters designate corresponding parts throughout the several views and in which the numeral 1 designates the wide portion of a four-in-hand tie which forms the front flap when tied, the numeral 2 the neck portion of the tie and the numeral 3 the narrow or rear flap of the tie when used. Whereas the ordinary four-in-hand tie is cut and folded so that the side edges of both the narrow and wide portions thereof are straight, even though tending to converge toward the neck portion, my invention contemplates the cutting and the folding of the material forming the wide portion of the tie on a curve or arc. This curve or arc is clearly shown in Figures 1 and 2 of the drawing and designated by the numeral 4. While the lower portions of the wide section 4 of the tie may be or appear to be straight or parallel, the same in fact are also curved. The principal portion of the curve extends from the widest portion of the section 4 to the neck portion 2, as it is this portion of the tie which is embodied in the knot to be formed.

This tie is also provided with a lining 5, made of the usual or any desired material. The edges of this lining are also cut on a curve or arc as shown at 6 in the drawing, and this curve or arc is coincident to the curve or arc 4 on which the body of the tie proper is cut and folded. This liner 6 is stitched as shown at 7 to assist in the formation of a drape in the material below the knot, and this particular feature is covered by Patent No. 2,123,900 and, therefore, does not specifically form a part of this invention.

Also forming part of this invention, however, is the auxiliary or extra liner 8, which is a short section applied to the liner 5 at the widest portion of the tie between the neck portion 2 and the lower end of the liner, as best shown in Figure 2 of the drawing. The side edges of this auxiliary or extra liner 8 are also cut on an arc or curve as shown at 9 and the curvature is coincident to the curvature 6 of the liner 5. The liners 5 and 8 are stitched in place within the folds of the body of the tie in the usual manner, as best illustrated in Figures 6 and 7 of the drawing.

Usually the body of a tie is made of silk, although synthetic materials have been and may be used in the embodiment of my invention. While as above, I have stated that the liners 5 and 8 may be made of the usual liner material, same may be made of any desired material, such as the material of which the tie proper is constructed. To be effective, for carrying out the purposes for which this invention is designed, the curvature of the body of the tie, the liner 5 and the liner 8 must extend from a position at least

at the bottom of the liner 3 and extend into the neck portion, as best shown in Figure 2 of the drawing.

When a tie, constructed as above described and shown in the drawing, is tied in the usual manner of a four-in-hand, it will automatically produce a large, full, V-shaped knot, substantially identical to the well known "Windsor knot." Thus all who know how to tie the ordinary four-in-hand will be in position, with the use of my improved tie, to achieve the results desired, namely produce a "Windsor knot" without actually learning the intricacies involved.

From the foregoing description of the construction of my improved tie, the method of making same and the application thereof to use will be readily understood, and it will be seen that I have provided comparatively simple, inexpensive and efficient means of carrying out various objects of the invention.

While I have particularly described the elements best adapted to perform the functions set forth, it is apparent that various changes in form, proportion and in the minor details of construction may be resorted to, without departing from the spirit or sacrificing any of the principles of the invention.

Having thus described my invention, what I claim is:

A necktie of the four-in-hand type comprising an elongated body formed of fabric and having front and rear plies, said body having top and bottom end sections and a narrow intermediate section of appreciably less width than the end sections, the top section being of greater width than the bottom section, said end sections having opposite side edges following elongated curves for a portion of their length and merging into side edges of the intermediate section, a flat main liner formed of the fabric and extending longitudinally of said body between the front and rear plies thereof and having a portion passing through the intermediate section and along top and bottom sections of the body throughout the major portion of the length thereof and having side edges spaced inwardly a substantial distance from and in parallel relation to the curved side edges of the body and a one piece auxiliary liner formed of fabric and extending flat against and secured to the wide end portion of the main liner throughout a major portion of said length thereof, the auxiliary liner having side edges spaced inwardly a substantial distance from and in parallel relation to the curved side edges of said main liner whereby said liners provide progressively increasing support for said top end section from the side edges thereof toward the longitudinal center line to permit the formation of a relatively wide V-knot having a smooth curved surface by tying a conventional four-in-hand knot.

MAX J. COHAN.
